UNITED STATES PATENT OFFICE.

EMANUEL W. SWEIGARD, OF CHICAGO, ILLINOIS.

PRINTING-FRAME CLAMP.

1,146,974.

Specification of Letters Patent. Patented July 20, 1915.

Application filed August 24, 1914. Serial No. 858,174.

To all whom it may concern:

Be it known that I, EMANUEL W. SWEIGARD, a citizen of the United States, residing at Chicago, in the county of Cook and State 5 of Illinois, have invented certain new and useful Improvements in Printing-Frane Clamps, of which the following is a specification.

My invention relates to printing frames 10 and has particular reference to means for clamping the back of the frame against the front and against the negative and sensitive paper or metal on which blue print or half tone reproductions are to be made.

15 The objects of the invention are to provide a clamping frame for the printing back frame which shall be convenient to manipulate, which shall be adjustable to vary the degrees of pressure uniformly, which shall 20 be comparatively inexpensive to make, and which shall be particularly adapted for the flexible type of back and the use of atmospheric air pressure for forcing the back and front against each other, or for closely 25 compressing a negative and sensitized sheet to be exposed to light during the printing process.

With these general objects in view the invention consists of the novel construction, 30 combination and arrangement of parts hereinafter described in detail, illustrated in the accompanying drawing and incorporated in the appended claims.

In the drawing—Figure 1 is a plan elevation 35 of a printing frame embodying the present improvements, showing the rear side or back of the frame with the clamping frame portion of the back closed in full lines and shown open in dotted lines. Fig. 2 is an 40 enlarged section taken substantially on line 2—2 of Fig. 1. Fig. 3 is a similar view showing a changed position of clamp or open or released position, handle 26 not being shown. Fig. 4 is substantially a section on line 4—4 45 of Fig. 2. Fig. 5 is a top plan view of Fig. 2. Figs. 6, 7 and 8 are modifications. Fig. 9 is a perspective view of the combined pivot and nut shown on a smaller scale in Figs. 2, 3 and 4. Fig. 10 is a modification in which 50 the pivot and nut of Fig. 9 are separated and placed at opposite ends of the bolt.

In the several views 2, 3, 4 and 5 are the sides or rails of a frame for the back of the structure known as a whole as "printing frame." These rails or sides are not joined 55 together at the corners, but are separated as indicated by dotted lines to open or release the back of the printing frame, the front frame portion of which is indicated as 60 with a ledge around its four sides indicated at 7, said ledge supporting the usual glass front 8 with which the back 9 cooperates to hold a negative 10 and a sensitized sheet of metal, paper or fabric 11. The frame 6 has its corners rigidly joined and a 65 plan view of it is substantially a plan view of the frame 2, 3, 4, 5 with the dotted lines omitted, and a series of bolt holes (shown in elevation in Figs. 2, 3 and 4) 12. As shown in Figs. 2, 3, and 4, the bolt holes 12 are provided with parallel sides in one direction and with relatively inclined sides transversely of said direction. Transversely of a rail of the frame 6 the hole is tapered, or enlarged upwardly, to permit the angular 70 movement of the bolt 13 indicated by comparing Figs. 2 and 3. On the lower end of the bolt is its head 14 which engages the underside or front face of the rigid frame 6. The upper end of each bolt 13 engages a 75 plain bore 15 in the separable frame 2, 3, 4, 5 and at least two bolts are provided for each of the four rails of this frame. The meeting edges of the rails 2 to 5 may be either mitered as shown or parallel, the 80 particular configuration at their juncture not being essential for the purposes of the present invention. Figs. 2, 3 and 4 represent either one of the four rails 2 to 5 and the description in connection with the rail 5 will 85 therefore suffice for all. The rail 5 is moved out of its engagement with the back 9 by a sliding transverse movement, and in order to facilitate its clamping to and release from the back 9 without resorting to the tedious 90 and time-consuming method of tightening down a nut on the rail 5, this rail has secured to its upper surface by means of screws 16 and 17 a plate 18, from the edges of which rise perpendicularly segmental-form sides 100 19 and 20 between which sides is mounted a cam-head 21 which is bifurcated by a slot

22 for the bolt 13 which passes through a bore 23 in the plate 18. Eccentrically and pivotally mounted in said cam head is a cylindrical nut 24 which has a threaded bore 25 that is engaged by the threaded end of the bolt 13. The cam 21 is provided with a handle 26 and the cam is adjusted on the threads 25 to vary the degrees of compression of the back frame against the front frame by swinging the handle 26 as seen in Fig. 4 over to the left to clear the sides 19 and 20 so that the nut 24 may be turned on the threads of the bolt. In Fig. 10 is shown a modified form of bolt where the lower end of the bolt is threaded and carries a wing nut 27 by means of which the adjustment is made without turning the cam as indicated. In this figure a pivot-pin 28 is substituted for the pivot 24 and passes through the bolt 29. The pivot pin 28 performs the same function as the cylindrical member 24 minus its threaded bore 25.

In Figs. 6, 7 and 8 are shown modifications in which a plate 30, held by screws 31 and 32, is substituted for the plate 18 in the preferred construction. On the plate 30 is a cam disk 33 which forms an integral part of the plate and co-operates with an opposing cam disk 34 which is revolubly mounted on a bolt 35 provided with a wing nut 36 by means of which the force of the cam is adjusted. The cam disk 34 is provided with wings 37 and 38 with the aid of which the member is turned on the member 33. The bolt 35 has its head 39 engaged with a casting secured to the frame 6 by means of screws 41 and 42 and having a slot 43 which permits lateral movement of the bolt corresponding to the movement of the bolt 13. The cam surfaces 44 and 45 are given an inclination such that, when the cam is released, a half turn of the member 34 will release the rail 5 so that it may be tilted outwardly to clear the edge of the back 9. The back 9 is of the flexible type, having an edge 46 designed to be compressed between the rails 2 to 5 and the front 8 to make an airtight joint preparatory to exhausting air from between the front 8 and back 9 for the purpose of forcing them toward each other, features that form no part of the present invention and are not herein included.

The rail 5, and likewise the other rails 2, 3 and 4, as explained, has that portion of its under-surface which is exterior of the ledge 7 concaved transversely as at 47, 47 which facilitates its turning movement from position shown, as for instance, in Figs. 2 and 7 to the position shown in Figs. 3 and 8. The concavity also insures a closer contact between that portion of the under side of the rail which overlies the edge 46.

In operation the cams are released by swinging the handles over in the opposite direction of the positions of Figs. 2 and 4,

or giving a half turn to the cam disks 34, then tilting the rails over to their dotted line positions in Fig. 1, then removing the back 9 and inserting negative and sensitized sheet of paper or metal, then replacing the back 9 and the rails 2 to 5 and tightening the latter down on the edges 46 of the back and finally exhausting the air from between back and front as through a suitable hole 48 (Fig. 1) connected with an exhaust pump 75 (not shown).

I claim as my invention—

1. The combination with a printing frame having a front and back, of a series of rails forming a frame for said back and overlying the frame portion of said front, said front and back frames having bolt holes therethrough, a series of bolts engaging said front and back frames and movable angularly in said front frame, cams on said bolts by means of which said front and back frames are clamped together, and adjustable means on said bolts for varying the clamping force of said cams.

2. The combination with a printing frame having a front and back and a frame for each the sides of the back frame being free of each other and movable away from each other, of clamping devices for temporarily clamping said front and back frames together, and adjustable means for varying the compressive forces of said clamping devices.

3. The combination with a printing frame having a front and a back and a perforated clamping frame for each, of bolts engaging said frames and permitting lateral movement for each side of the back frame, a threaded nut on each of said bolts, and co-operating cam surfaces between each said nut and said frame for clamping the front and the back together.

4. The combination with a printing frame of perforated frames for the front and back, respectively, of said printing frame, the back frame having rails free of each other and movable away from each other, of clamping devices connecting said front and back frame, and means for varying their operativeness as to degrees of clamping force exerted by same.

5. The combination with a printing frame having a front and back and a perforated frame for each, the frame for the back having separable sides movable toward and from each other on parallel lines, of threaded rods engaging the frames for said front and back and movable angularly in the front frame, a nut on each of said rods, and a cam pivotally mounted on said nut for forcing the front and back frames together.

6. The combination with a printing frame having a front frame portion 6 and a back frame consisting of rails 2, 3, 4 and 5, said front frame having bolt recesses 12 up-

wardly and enlarged, the bolts 13 engaging my hand in the presence of two subscribing the rails of the back frame, the bearing witnesses.

plates 18 having cam-guide sides 19 and 20,
the nuts 24 of cylindrical form, and the cams
5 21 pivoted on said nuts to bear against said
plates 18.

In testimony whereof I have hereunto set

EMANUEL W. SWEIGARD.
